UNITED STATES PATENT OFFICE

1,963,305

SEMIROTARY WIRE FABRIC MACHINE

William A. Kilmer, De Kalb, Ill., assignor to The American Steel and Wire Company of New Jersey, a corporation of New Jersey

Application June 12, 1933, Serial No. 675,491

17 Claims. (Cl. 140—9)

This invention relates to wire fabric machines, and more particularly to a semi-rotary wire fabric machine adapted to make a hexagon mesh fabric having longitudinal untwisted line wires 5 and adapted particularly for use as fencing and concrete reinforcement material.

The machine comprises drum twisting heads of such shape as to form and to hold the mesh in alignment while being acted upon by the 10 twisters, and also includes novel means for guiding and distributing the mesh wires in the drum twisting head. A novel mechanism is also provided for holding the mesh wires in the drum twisting head during the twist which is made by 15 the spindles.

Other features of the machine, such as novel guides for the mesh and strand wires, pull-out rolls, shearing and reeling mechanism and automatic stopping mechanism for the machine 20 adapted to operate when a predetermined length of fabric has been completed, all will be brought out specifically in the following specification.

In the drawings:

Figure 1 is a top plan of the wire fabricating 25 machine.

Figure 2 is an enlarged plan of the twisting drum drive mechanism.

Figure 2^a is an enlarged plan of the wind-up drum drive mechanism.

Figure 3 is an enlarged plan of the wire fabricating machine, showing the opposite side of 30 that shown in Figures 2 and 2^a.

Figure 4 is a side elevation of the apparatus shown in Figures 2 and 2^a.

Figure 5 is a sectional elevation taken on the 35 line V—V of Figures 2 and 2^a.

Figure 6 is a side elevation of the apparatus shown in Figure 3.

Figure 7 is an end elevation of the apparatus 40 shown in Figure 3 with the twisting drum shown in section.

Figure 8 is an end elevation of the apparatus shown in Figure 2, partly in section.

Figure 9 is a sectional elevation of the wire 45 threading and twisting mechanisms.

Figure 10 is a sectional elevation taken on the line X—X of Figure 9.

Figure 11 is a sectional elevation of the wire 50 twisting spindle and spindle drive mechanism.

Figure 12 is a sectional plan taken on the line XII—XII of Figure 11.

Figure 13 is a side elevation of the twisting spindle drive mechanism.

Figure 14 is a top plan showing the twister 55 heads in rotative position.

Figure 15 is a top plan showing the twister head segments in shifted position.

Figure 16 is a sectional plan showing the twister head shifting mechanism with the twister head 60 segments in the position shown in Figure 14.

Figure 17 is a similar view with the twister head segments in the position shown in Figure 15.

Figures 18 and 19 are sectional elevations taken on the lines XVIII—XVIII and XIX—XIX, respectively, of Figure 14. 65

Figure 20 is an elevation showing a section of the twister drum, rotary tooth bar and twisting spindle head.

Figure 21 is a sectional elevation taken on 70 the line XXXI—XXXI of Figure 20.

Figure 22 is a top plan of apparatus shown in Figure 21, partly in section.

Figures 23, 24 and 25 are detail views of the pull-out drum. 75

Figures 26 and 27 are detail views of the shearing apparatus.

Figure 28 is a plan of a section of wire fabric.

Figure 29 is an elevation showing a device for automatically stopping the wire fabricating machine. 80

Figure 30 is a sectional elevation taken on the line XXX—XXX of Figure 29.

For convenience, the description of the machine of this invention will be divided into several main groups. 85

Twisting spindles and means for distributing the Wires thereto

The selvage and line wires are led from suitable 90 reels (not shown) under pipe rolls 2 and 2^a and over sheaves 3 and under sheaves 4 and then up through hollow twisting spindles 5. The mesh wires are led from suitable reels (not shown) under other pipe rolls 6 and 6^a and up over and 95 under suitable sheaves 7 and 7^a, respectively, around spindles 5 and then up through hollow segments 8. All of the wires are adapted to be pulled into the machine by the action of the twisting drum D. The segments 8 are mounted 100

transversely of the machine in two rows at the opposite side of the spindle segments 9. The segments are provided with quills through which the mesh wires are led, and the twisting spindles 5 are also provided with quills through which the strand and selvage wires are led. The segments 8 are shifted back and forth to distribute the mesh wires in the twisting drum head wire, thereby forming the hexagon mesh of the fabric by the reciprocating movement of the shifting bars 10 and 12, in a manner presently to be described. The twisting spindles, which are made up of spindle segments 8 and 9, and spindle 5 are arranged so that the segments 8 are rotated at the proper time by the spindle gear 17. One of the spindle gears 17 is secured to each of the spindles 5, and these gears are actuated by a reciprocating rack bar 14.

The center spindle segments 9 are provided with projections 9a on either side that fit in ways 15 provided in spindle segments 8 for the purpose of holding the segments in proper relation. The spindle segments 8 and 9 are also provided with grooves adjacent their upper ends to receive the brass retainers 16 which are secured to the shifting bars 10 and 12, for the purpose of holding the segments in proper relation with the shifting bars.

The main drive shaft of the machine is designated by the numeral 18, and carries fast and loose pulleys 19 and 20, respectively. The motion of the main shaft 18 is transmitted to a second shaft 21 through a bevel pinion 22 and bevel gear 23, and from the shaft 21 power is transmitted to a third shaft 24 through a pinion 25 and gear 26. Secured to the shaft 24 is a mutilated gear 27, which is adapted to mesh with a mutilated pinion 29 secured to a crank-shaft 28. Fastened to the shaft 28 is a crank disk 30, to which a pitman or connecting-rod 32 is secured by a pin 31. The connecting-rod 32 is connected through a pin 33 and cross-head 34, which slides in ways in a bracket 35 to the rack bar 14. The rack bar 14, as before mentioned, engages the pinions 17 on the hollow twisting spindles 5 and when the teeth on the mutilated gear 27 engage the teeth on the mutilated pinion 29, it causes the crank-shaft 28 to turn one-half of one revolution, thereby causing the twisting spindle segments to revolve the desired number of times around the strand or mesh wires. The mutilated gear 27 on the shaft 24 is provided with teeth for about one-third of its circumference, or a sufficient number of teeth to turn the mutilated pinion 29 one-half of a revolution. The remaining distance of the circumference of the mutilated gear is left blank. Attached to the side of the gear 27 is a ring 38 which engages a shoe 39 on the mutilated pinion 29 so as to lock the pinion at each one-half revolution. The pinion 29 is mutilated by providing a double width tooth to the pinion to receive the blow from the mutilated gear 27, and a recess is provided in the gear 27 to receive this double width tooth.

Secured to the gear 26 is a sleeve gear 40 which engages the gear 41 secured to a shaft 42. The shaft 42 has a cam plate 43 secured to its outer end, which plate carries cams 44 and 45.

A connecting-rod 46 has a roller 47 at its one end which is mounted to operate in the way between the cams 44 and 45, and the other end of the rod 46 is connected to the front shifting bar 10 so as to reciprocate said bar as the cams are rotated. The front and back shifting bars 10 and 12, respectively, have short racks 49 on their in-

ner surfaces at their ends opposite the cams 44 and 45, and these racks engage opposite sides of a toothed pinion 50 which causes the back shifting bar to reciprocate in a direction opposite from the front shifting bar. After the spindle segments have been given the required number of revolutions, as before described, the roller 47 and the connecting-rod 46 are actuated by the cams 44 and 45, thereby reciprocating the shifting bars 10 and 12 which, in turn, move the spindle segments transversely of the machine so as to distribute the mesh wires and form the mesh. After the shift has taken place and the segments have returned to the normal position, the shifting bars are locked and held in this position during the twisting operation by a locking lever 60.

A pinion 51 is secured to the main drive shaft 18 and meshed with a gear 52. Secured to a shaft 53 is a pinion 54 which meshes with a gear 55 on a shaft 56. The shaft 56 carries a cam 57 which operates against a roller 58 carried by suitable lever and linkage mechanism which, in turn, rocks a shaft 59. The shaft 59 is connected by other suitable lever and linkages to the locking lever 60 and operates the lever 60 to engage and disengage in suitable recesses in the shift bars 10 and 12. When the locking lever 60 is engaged in the recesses provided in the shifting bars 10 and 12, the crank-shaft is given one-half of a turn, causing the spindle segments to revolve two and one-half times around the camshaft for each cycle or for each revolution of the shaft 24 on which is mounted the mutilated gear 27. The spindles are caused to revolve in alternately opposite directions so that the mesh wires, which are caused to wrap around the segments in one direction or rotation, are unwrapped by the reverse direction of rotation of the spindles.

The fabric provided as above described is what is known as a single hinge, that is, it can be folded at each spindle spacing. If the spindles were caused to revolve two or any even number of times and the direction of the shift of the segments remained the same, then the fabric produced would be rigid and could not be folded at any point.

The twister head type drum and associated parts

The twisting drum, which is designated generally by the letter D, has a shaft 67 which is journaled on the frame of the machine. A bevel pinion 62 on the drive shaft 18 is meshed with a bevel gear 63 on a shaft 64 which shaft, in turn, carries a worm 65 meshed with a worm wheel 66 on the drum shaft 67. Mounted on the drum D 130 is a series of tooth bars 68, provided with covers 69. The tooth bars have alternate slots 70 for the strand wires which register with the twisting spindles and alternate slots 71 for the mesh wires, which are midway between the slots 70 and the spindles and are of such shape as to form and hold the mesh wire being acted upon by the twisters. The teeth are arranged in a circular series coaxial with the drum and are retained by clamp bars 72 secured to the drum by suitable screws. 140

Each tooth bar 68 has a longitudinal recess extending the entire length of the bar for the reception of a rack 73. The bars 68 are provided with twister pinions 74 at each of the slots 71, which pinions are meshed with the rack bars 73. 145 The twister pinions 74 have their axes transverse to the racks and all the twister pinions in each bar 68 are obviously operated by the single rack bar when it is reciprocating in a manner to be described.

Rotation of the twister pinions 74 effects an intertwisting of the mesh wires, securing said mesh wires together to form the mesh. The twister pinion is formed with slots adapted to be alined 5 with the slots 71 in the bars, which is of such a size as to receive two mesh wires, but its width is only slightly greater than a single wire so that when two wires are fitted in the twister pinion they will be rotated at equal distances from the 10 axis thereof and will be necessarily twisted one upon the other when rotary movement is imparted to the twister pinions. If it is desired, suitable hard tool steel wear plates may be inserted in the twister pinions in order to prevent wearing 15 of the slots in the use of the machine.

In addition to the function of the tooth bars as a support for the twister pinions they also serve as a wire guide and form for the mesh and strand wires, and it will be noted that the teeth on the 20 bars 68 are shaped to conform with the shape of the mesh of the fabric and that they are reduced toward their outer extremes so as to allow for the release of the completed fabric. The rack bars 73 carry anti-friction rollers 75 at their opposite ends. Secured to either side of the frame of the machine are cam plates 76 on which are secured inner cams 77 and outer cams 78 between which the anti-friction rollers 75 of the 25 rack bars 73 are adapted to operate. The rollers 75 on the left-hand ends of alternate rack bars 73 contact with the inner cam 77 for movement of the bars to make left-hand twists, and for alternate right-hand twists the rollers 75 on the right-hand ends of the other bars 73 contact with 30 the right-hand inner cam 77. For the return of the rack bars the rollers 75 on the ends of the bars opposite the ends engaged with the inner cams 77 are engaged with the outer cams 78.

The timing of the twisting drum is so proportioned that each tooth bar 68 will travel one tooth space for each cycle of the machine or for one completed mesh, and is so set in relation to the twisting segments that as soon as the segments have shifted, carrying with them the mesh wires, the tooth bars are in position to receive the mesh wires. When the shifting bars have moved, carrying with them the segments and mesh wires, the mesh wires will be moved into line with the slots in the drum, and as the bar 45 advances the mesh wires will be carried into the twisting slots and the line wires into alternate slots on a line tangent to the drum.

In order to hold the wires in the slots in the twisting drum, a rotary tooth bar 82 is provided 50 which is mounted on a shaft 81. Secured to the twisting drum shaft 67 is a gear 79 which meshes with a pinion 80 secured to the shaft 81. The rotary tooth bar 82 is so shaped and timed that its bar teeth will travel between each tooth space 55 of twisting tooth drum when motion is imparted to the drum shaft 67. The rotary tooth bar is located above the shifting bars 10 and 12 so that the teeth will clear the spindle segments. When the twisting tooth drum advances to the point 60 where the spindle twisting takes place the bar tooth on the rotary tooth bar 82 depresses the wires in the slots of the active twisting tooth bar 68 so that the spindle twisting takes place on the shaped portion of the twisting bar teeth and below the beveled portion thereof. If the wire is 65 not held so that the spindle itself is down below the beveled portion of the twisting tooth on the bar 68 the spindle twist of the mesh will prevent the mesh being forced down into the slots and 70 consequently when the drum twisters revolve the 75

mesh wires will not properly enter the twister pinions, and will result in the mesh wires being sheared.

Other means may be used or substituted for the rotary tooth bar 82 for holding the wires in proper position in the twister drum, if desired, without departing from the scope of this invention. 80

Pull-out drum, rolls, shears and reel and their actuating mechanism 85

After the mesh has been completed by the twisting drum it is pulled out by the action of a pull-out drum 84 on a shaft 84^a provided with teeth 85 arranged in a circular series coaxial with the drums. The teeth of the drum 84 are made to conform to the mesh that is made by the twisting drum and are arranged to enter said mesh. Motion is imparted to the drum 84 as follows: Secured to the worm wheel 66 which is attached to the twister drum shaft 67 is a bracket 86. On the bracket 86 is fastened a rope drive 87 which extends around a drum 68 which is free to turn on the twister drum shaft 67. Attached to the drum 88 is a sprocket 89 which is connected to the sprocket 90 on the pull-out drive shaft 84^a by a chain 91. 90

From the pull-out drum the fabric goes over a series of bottom rolls 92 and under a top roll 93 which is located directly over one of the bottom rolls and is held in close contact with the fabric by means of springs 94. The rolls 92 and 93 are driven by suitable gearing from the pull-out roll shaft 84^a. 95

The shears and their actuating mechanism are 100 generally similar to the shears shown in my prior United States Patent No. 1,158,505, dated November 2, 1915, and reference is made to this patent having detailed description and disclosure thereof. The shears of my prior patent have been 105 modified slightly by the provision of a novel means for holding the fabric prior to the shearing, and this novel means will now be described.

The movable cross-bar 95 for the upper shear 110 95 is provided with a series of hollows for guide pins 96. A hold-down angle bar 97 is secured to the pins 96 and springs 98 are mounted around the pins 96 and normally bias the angle bar 97 downwardly below the edge of the upper knife 95. The normal location of this angle bar 97 in relation to the top shear knife 95 is a trifle lower than the bottom edge of the knife and when motion is applied to the shear the upper shear knife 95 descends, carrying with it the angle bar 97. When the angle bar 97 makes contact with 120 the fabric to be sheared on the lower shear knife 95 the angle retracts and serves to clamp the fabric in position. After shearing the fabric the upper shear knife 95 returns or retracts and due to the energy of the springs 98 the hold-down angle bar 97 moves down below the lower edge of the knife blade 95 so as to hold the fabric below the edge of the upper knife and permit free movement of the fabric forwardly beyond the knife. 125

The particular arrangement of triple reels and 130 their carriers are shown and described in my prior United States Patent No. 1,199,795, dated October 3, 1916, and reference is made to said patent having a detailed description thereof. The drive and operating mechanism for the reels 135 as used in the present machine has been modified over that shown in my prior patent and will be described below. 140

The reel carrier shaft is designated by the numeral 100 and carries a rotatable sleeve 101. 150

- Motion is transmitted to the sleeve 101 by means of a pinion 102 meshed with a gear 103 on a shaft 104. The shaft 104 carries a sprocket 105 connected to a sprocket 106 on a shaft 107 by a chain 108. The shaft 107 carries a second sprocket 109 which is connected to a drive sprocket 110 on a twister drum shaft 67 by a chain 111. On the other end and integral with the sleeve 101 is a pinion 112 which meshes with a gear 113 secured to a sleeve 114 which is rotatable on the reeling shaft 115. One of the gears 113 and sleeves 114 is provided for each reeling shaft and is in constant motion when the machine is in operation.
- 15 Journaled on the gear 113 are mitre gear segments and shafts 116 and 117, respectively. Secured to one end of the mitre gear shaft 117 is a lever 118 which carries a brake band 119 which causes frictional contact with a flanged drum or pulley 120 which is secured to the reeling shaft 115. Secured to the shaft of the mitre gear 116 is a lever 121 which is connected to the sleeve 114 by a link 123. The sleeve 114 has a sliding fit on the shaft 115 and movement is imparted to the sleeve 114 through a collar 124 which is held in a recess on the sleeve and is operated by a bearing member 125 carried by a rocking lever 126 which, in turn, is pivotally mounted on the frame of the machine. The lever 126 is rocked by a slide link 127 which has its free end provided with a roller 128, which rides in a cam 129. The cam 129 is free to slide on the sleeve 101, but is held from revolving by slide arms 130 retained in a housing on the machine frame. Secured to the slide arms 130 is a yoke 131 at which is secured a rope 135 which passes over a sheave 132 and is connected to a weight 133.
- 20 It will be seen from the above that this weight 133 has direct bearing with the frictional contact of the band 119 on the flanged drum or pulley 120. The weight 133 can be increased or diminished while the reeling is in operation so as to give the desired amount of pull necessary for reeling.
- 25 A pair of triple-reel arms 200 and 201 are secured to the reel shaft 100, as is a rope drum 202 which is similar to the rope drum 88. A sprocket 203 is mounted for rotation on the reel shaft 100, and has secured thereto a rope arm 204. A plurality of ropes 205 are made to encircle the rope drum 202 and one of the ends thereof is attached to the rope arm 204 by means of hooks 206 and the other ends of the ropes 205 are attached to screws 207 which function to regulate the tension on the ropes.
- 30 The sprocket 203 is adapted to be driven by a chain 208 from a sprocket 209, the latter being secured to a shaft 211. A sprocket 210 is also secured to the shaft 211, and adapted to be driven by a chain 212 from a sprocket 213, the latter being secured to the twister pull-out drum shaft 67.
- 35 The reel shaft 100 is held against rotation by means of a slide 214 which engages a recess on a disk 215 which is secured to the shaft. The cross-bar 95^a of the shear mechanism receives movement from a shaft 216, the latter having secured thereto a cam 217. A roller 218 is mounted on a lever 219 which is pivoted in such manner as to enable the engagement of the roller with the cam 217. A shaft 220 is connected at one end to the lever 219 and at its other end to one arm of a bell-crank lever 221, the latter being restrained from pivotal movement by means of a spring 221^a. A link 222 is connected at one of its ends to the slide 214 and at its other end to the other arm of the bell-crank 221. The function of the spring 221^a is to hold the slide 214 in a recess in the disk 215, in order to restrain the rotation of the reel shaft 100.
- 40 A lug 214^a is secured to one side of the slide 214 and adapted to engage a trip slide 223 when the slide 214 is withdrawn from a recess in the disk 215. Movement is imparted to the trip slide 223 by means of a pivoted lever 224 which is provided with a roller adapted to be contacted by a cam 225 which is secured to the reel shaft 100. A spring 224^a is connected with the pivoted lever 224 in such manner as to hold the roller against the face of the cam 225 and slide 223 in the path of the lug 214^a on the slide 214.
- 45 The shear operating shaft 216 makes only one revolution when the fabric is sheared during which the cam 217 rocks the lever 219 and moves the shaft 220, causing the slide 214 to be withdrawn from a recess in the disk 215. The reel shaft 100 is caused to turn by means of rope friction when movement is given the twister drum shaft 67, until the slide 214 enters the next recess in the disk 215.
- 50 While the reel shaft 100 is turning, provision is made for holding the slide 214 out of engagement with a recess in the disk 215 until the recess is out of its path, thus enabling the shearing of the fabric only when the weaving has stopped. The reel shaft 100 will be permitted to rotate after the shearing operation, in order to present the completed and sheared roll of fabric for removal, and the reeling of the new roll at the next operating station.
- 55 When the reel has been wound and the reel carrier has moved so that another reel comes into position, then the completed roll is in position to be removed and the frictional contact of the band 119 on the drum 120 is released through the roller 128, and the slide arm 127 contacting with the depressed portion of the cam 129 causes the reeling to stop.
- 60 *Means for automatically stopping the operation of the machine*
- 65 As a means for stopping the operation of the machine when a predetermined amount of fabric has been wound on the reel, I provide a hook sheave 140 which is free to turn on a hollow shaft 141. One side of the sheave 140 is provided with a jaw clutch face which operates against a jaw clutch member 142 secured to the hollow shaft 141. Mounted on the shaft 141 is a lever 143 which operates a belt shifter 144 when motion is imparted to the hollow shaft 141 to move the drive belt from the fast pulley 19 to the loose pulley 20, thereby stopping the machine.
- 70 Attached to the hook sheave 140 is a rope 145 which carries a weight 146. The sheave 140 is held stationary and out of engagement with the clutch 142 by means of a hook lever 147 which engages a tooth 148 on the sheave 140 and is released through a cam disk 149 contacting with the upper end of the lever 147, so as to cause the lever to disengage from the tooth 148 on the sheave 140. Motion is imparted to the cam disk 149 by means of suitable gearing operable by a worm wheel 150 which is, in turn, driven by a worm 151 secured to the twister drum shaft 67.
- 75 In order to provide for automatically stopping the machine when different lengths of fabric have been made and reeled, I provide an automatic measuring mechanism consisting of a pin 152 which is held in a housing 153 formed integral with a gear 154 of the drive gearing for the cam 150

disk 149. The pin 152 is adapted to engage holes in a disk 155 which is integral with a second gear 155^a of the cam disk drive.

By withdrawing the pin 152 the cam disk 149 can be set by turning the gear 154 to register the pin 152 with any hole provided in the face of the disk 155 carried by the gear 155^a, that is, changing the location of the high point of the cam disk 149 relative to the upper end of the lever 147 and thereby changing the length of fabric which is made and reeled prior to the tripping of the lever 147 and stopping of the machine. A stationary index plate 156 is shown for indicating the various lengths of fabric that will be made by the various settings of the cam disk, as described above. Various combinations of gearing, of course, may be substituted for the gearing shown to vary the lengths of fabric beyond that provided for in the adjustments shown and described.

It will be understood, of course, that the lock pin 152, the housing 153 and disk 155 may be eliminated, and the gearing alone be provided for driving the cam disk 149 if it is not desired to adjust the lengths of fabric to be made on the machine.

While I have shown and described one specific embodiment of my invention, it will be understood that I do not wish to be limited thereto since various modifications may be made without departing from the scope of my invention, as defined in the following claims.

I claim:

1. In a wire fabric machine, means for delivering a series of strand wires, means for delivering a series of mesh wires, means operating in alternating opposite directions for twisting at least two mesh wires around each strand wire, a twisting drum, means on said drum for twisting at least two adjacent mesh wires around one another in alternating opposite directions, stationary slots on said twisting drum for receiving said strand wires, and extraneous means for positioning and maintaining said strand wires and said mesh wires on said drum.

2. A wire fabric machine comprising means for delivering a series of strand wires, means for delivering a series of mesh wires, means operating in alternating opposite directions for twisting at least two mesh wires around each strand wire, means operating in alternating opposite directions for twisting at least two adjacent mesh wires around one another, means for assisting the fabric from said last named twisting means, means for holding said fabric against movement, means for shearing said fabric, and a plurality of reeling means adjacent said shearing means.

3. A wire fabric machine comprising means for delivering a series of strand wires, means for delivering a series of mesh wires, means operating in alternating opposite directions for twisting at least two mesh wires around each strand wire, means operating in alternating opposite directions for twisting at least two adjacent mesh wires around one another, means for assisting the fabric from said last named twisting means, means for holding said fabric against movement, means for shearing said fabric, a plurality of reeling means adjacent said shearing means and means for automatically stopping the operation of all of said mechanism.

4. A wire fabric machine comprising a plurality of spindle assemblies, each assembly consisting of hollow segments for delivering line and mesh wires, means for rotating said spindle as-

semblies, means for reciprocating said spindle segments, a twisting drum provided with stationary and twisting slots, means for rotating said twisting slots in alternating directions, and extraneous means for holding said mesh and said line wires while being acted upon by said twisting slots and said rotating and reciprocating spindles.

5. A wire fabric machine comprising a plurality of spindle assemblies, each of which consists of hollow segments for the delivery of line and mesh wires, means for rotating each of said spindle assemblies, means for reciprocating the hollow segments for said mesh wires relatively to the hollow segments for said line wires, a twisting drum adjacent said spindle assembly, alternately disposed twisting and stationary slots on said twisting drum, means for rotating said twisting slots in alternating directions, and an extraneous means for positioning and maintaining a mesh wire from each of two adjacent spindle assemblies in each of said twisting slots and a single line wire in each of said stationary slots.

6. A wire fabric machine comprising a plurality of spindle assemblies, each of which consists of a plurality of hollow segments for delivering a line wire and a pair of mesh wires, means associated with each of said spindle assemblies for twisting said mesh wires about said line wire, means for separating said twisted wires, means associated with each of said spindle assemblies for positioning each previously twisted mesh wire adjacent a similar wire associated with an adjacent spindle assembly, a twisting drum provided with a plurality of alternating twisting and stationary slots, and means adjacent said twisting drum and said spindle assemblies for positioning and maintaining a line wire about which said mesh wires have been twisted in a stationary slot and for positioning and maintaining a wire from a pair of adjacent mesh wire segments in each of said twisting slots.

7. A wire fabric machine comprising a plurality of spindle assemblies, each of which is adapted to deliver a strand wire and a plurality of mesh wires, means for rotating each of said spindle assemblies, means for reciprocating said mesh wires in alternating directions, a twisting drum provided with a plurality of slots, means for rotating every other slot in said twisting drum, means for reversing the direction of twist of said rotating slots, means for positioning and maintaining a mesh wire from each of a pair of adjacent spindle assemblies in said rotating slots, and means for positioning and maintaining said strand wires in the stationary slots in said twisting drum.

8. In a wire fabric machine, a twisting drum having a multiplicity of alternately disposed stationary and rotary twisting slots, said rotary twisting slots comprising a plurality of longitudinally disposed tooth bars, an elongated longitudinally disposed cover for each of said tooth bars, a slotted pinion disposed at intervals between each of said tooth bars and said covers, a slotted journal for each of said pinions, and a longitudinal rack bar for rotating said pinions in alternating directions.

9. In a wire fabric machine a twisting drum having a multiplicity of alternately disposed stationary and rotary twisting slots, said rotary twisting slots comprising a plurality of elongated longitudinally disposed tooth bars, an elongated longitudinally disposed cover for each of said tooth bars, a slotted pinion disposed at intervals 150

- between each of said tooth bars and said covers, a slotted journal for each of said pinions, a longitudinal rack bar for rotating said pinions, means for reciprocating said rack bar in alternating directions, and clamp bars for rigidly securing said tooth bars and said covers to said twisting drum. 80
10. In a wire fabric machine, means for twisting at least two mesh wires around one strand wire, means for twisting at least two adjacent mesh wires around one another, means for assisting the fabric from said last named twisting means, in combination with means for supporting a plurality of removable reels, means associated with said supporting means for moving each reel into operative position, and means on said supporting means for frictionally driving each of said reels when in said position. 85
11. In a wire fabric machine, a plurality of spindle assemblies, a twisting drum adjacent said spindle assemblies, a rotary tooth-bar for positioning and maintaining wires from said spindle assemblies in said twisting drum, a pull-out drum for said twisting drum, spring tensioned rollers adjacent said pull-out drum, a shear adjacent said spring tensioned rollers, and a reel assembly provided with tensioned braking means. 90
12. In a wire fabric machine, a plurality of spindle assemblies, a twisting drum adjacent said spindle assemblies, a rotary tooth-bar for positioning and maintaining wires from said spindle assemblies in said twisting drum, a pull-out drum for said twisting drum, power driven spring pressed rolls for assisting the delivery of fabric from said pull-out drum, a shear adjacent said rolls, a reeling assembly adjacent said shear, in combination with automatically actuated means for stopping the operation of the combined mechanism in accordance with a predetermined operation of said reeling assembly. 95
13. In a wire fabric machine, automatic stop mechanism comprising a gear positively driven by said machine, a second gear rotated by said first named gear, a disk rotated by said second named gear, a cam on said disk, a spring tensioned pivoted lever adapted to be rocked from one of its ends by said cam, a hollow shaft, a hook sheave arranged for rotation on said shaft, a jaw clutch associated with one side of said sheave, a jaw clutch member secured to said hollow shaft, a lever mounted on said hollow shaft, means associated with said last named lever for stopping the operation of said machine, a hook on said pivoted lever for preventing the rotation of said hook sheave, in combination with means for changing the degree of travel of said cam relatively to the end of said pivoted lever. 100
14. In a wire fabric machine, automatic stop mechanism comprising a gear positively driven by said machine, a second gear rotated by said first named gear, a disk rotated by said second named gear, a cam on said disk, a spring tensioned pivoted lever adapted to be rocked from one of its ends by said cam, a hollow shaft, a hook sheave arranged for rotation on said shaft, a jaw clutch associated with one side of said sheave, a jaw clutch member secured to said hollow shaft, a lever mounted on said hollow shaft, means associated with said last named lever for stopping the operation of said machine, a hook on said pivoted lever for preventing the rotation of said hook sheave, in combination with means for changing the degree of travel of said cam relatively to the end of said pivoted lever, said means comprising a third gear positively driven by the 105
- first named gear, a housing formed integral with said gear, a pin mounted on said housing, a second gear associated with said cam disk drive, a disk formed integral with said last named gear, holes in said disk adapted to receive said pin and a stationary index plate for indicating the position of said pin. 110
15. In a wire fabric machine, automatic stop mechanism comprising a shaft, a hollow shaft mounted on said first named shaft, a sheave rotatably mounted on said hollow shaft, a jaw clutch face associated with one side of said sheave, a jaw clutch member secured to said hollow shaft, means associated with said hollow shaft for positively stopping the operation of said machine, a gear positively driven by said machine, a pinion mounted for rotation with said gear, a second pinion driven by said first named pinion, an apertured disk associated with said second pinion, a housing associated with said second pinion, and relatively movable to said disk, a reciprocal pin mounted on said housing and adapted to seat in the apertures in said disk, a pinion associated with said housing, a gear driven by said housing pinion, a disk rotatable by said last named gear, a rocking lever adjacent said cam, a cam on said disk for engaging one end of said lever, a hook associated with said sheave, a hook on the other end of said rocking lever for engagement with the hook on said sheave, and means for manually rotating said hollow shaft. 115
16. In a wire fabric machine, a rotatable shaft, a carriage on said shaft, a plurality of removable reels mounted on said carriage, means for rotating said carriage through said shaft, a rotatable sleeve on said shaft, a gear secured to said sleeve, means for rotating said gear, a plurality of shafts mounted on said carriage for rotating said reels and disposed radially about said sleeve, a sun-gear mounted on each of said shafts and in mesh with the gear on said sleeve, a pair of mitre gear segments journaled on each of said sun-gears, a pulley on each of said radially disposed shafts, a lever associated with one of each of each pair of said mitre gear segments, a brake-band carried by each of said levers and adapted for frictional contact with one of said pulleys, a sliding sleeve on each of said radially disposed shafts, a lever associated with the other of each of said mitre gear segments, a link connecting each of said levers and each of said sliding sleeves, a recess in each of said sliding sleeves, a collar in each of said recesses, a bearing on each of said collars, a pivoted rocking lever for each of said sleeves, and connected at one of its ends thereto, a second sleeve mounted on said rotatable shaft, a cam way associated with said second sleeve, a slide-link connected to each of said rocking levers, rollers on said links disposed in said cam way, means for preventing rotation of said second sleeve, and tension means for restraining said second sleeve from reciprocation. 120
17. In a wire fabric machine, means for twisting at least two mesh wires around one strand wire, means for twisting at least two adjacent mesh wires around one another, means for alternately reversing the operation of both of said twisting means, in combination with a rotatable shaft, a carriage mounted on said shaft, a plurality of removable reels mounted on said carriage, a rotatable sleeve on said shaft, a gear secured to said sleeve, means for rotating said gear, a plurality of shafts mounted on said carriage for rotating 125
18. In a wire fabric machine, means for twisting at least two mesh wires around one strand wire, means for twisting at least two adjacent mesh wires around one another, means for alternately reversing the operation of both of said twisting means, in combination with a rotatable shaft, a carriage mounted on said shaft, a plurality of removable reels mounted on said carriage, a rotatable sleeve on said shaft, a gear secured to said sleeve, means for rotating said gear, a plurality of shafts mounted on said carriage for rotating 130
19. In a wire fabric machine, means for twisting at least two mesh wires around one strand wire, means for twisting at least two adjacent mesh wires around one another, means for alternately reversing the operation of both of said twisting means, in combination with a rotatable shaft, a carriage mounted on said shaft, a plurality of removable reels mounted on said carriage, a rotatable sleeve on said shaft, a gear secured to said sleeve, means for rotating said gear, a plurality of shafts mounted on said carriage for rotating 135
20. In a wire fabric machine, means for twisting at least two mesh wires around one strand wire, means for twisting at least two adjacent mesh wires around one another, means for alternately reversing the operation of both of said twisting means, in combination with a rotatable shaft, a carriage mounted on said shaft, a plurality of removable reels mounted on said carriage, a rotatable sleeve on said shaft, a gear secured to said sleeve, means for rotating said gear, a plurality of shafts mounted on said carriage for rotating 140
21. In a wire fabric machine, means for twisting at least two mesh wires around one strand wire, means for twisting at least two adjacent mesh wires around one another, means for alternately reversing the operation of both of said twisting means, in combination with a rotatable shaft, a carriage mounted on said shaft, a plurality of removable reels mounted on said carriage, a rotatable sleeve on said shaft, a gear secured to said sleeve, means for rotating said gear, a plurality of shafts mounted on said carriage for rotating 145
22. In a wire fabric machine, means for twisting at least two mesh wires around one strand wire, means for twisting at least two adjacent mesh wires around one another, means for alternately reversing the operation of both of said twisting means, in combination with a rotatable shaft, a carriage mounted on said shaft, a plurality of removable reels mounted on said carriage, a rotatable sleeve on said shaft, a gear secured to said sleeve, means for rotating said gear, a plurality of shafts mounted on said carriage for rotating 150

said reels and disposed radially about said sleeve, a sun-gear mounted on each of said shafts and in mesh with the gear on said sleeve, a pair of mitre gear segments journaled on each of said 5 sun-gears, a pulley on each of said radially disposed shafts, a lever associated with one of each pair of said mitre gear segments, a brake-band carried by each of said levers and adapted for frictional contact with one of said pulleys, a 10 sliding sleeve on each of said radially disposed shafts, a lever associated with the other of each pair of said mitre gear segments, a link for con- necting each of said levers to one of said sliding sleeves, a rocking lever mounted on said carriage adjacent each of said sleeves and having one of its ends connected thereto, a second sleeve on said first mentioned shaft, a cam way associated with said second sleeve, a sliding link for each of said rocking levers and having a bearing disposed in said cam way, means for preventing for rotation of said second sleeve, and tension means for resisting the reciprocation of said 15 second sleeve.
